HAIR PRESSING COMB

James Duckworth, Chicago, Ill.

Application September 18, 1936, Serial No. 101,523

3 Claims. (Cl. 132—11)

This invention relates to a comb for use by beauty culturists.

When preparing hair for dressing it is desirable first to remove all artificial or natural kinks.

5 It has been found in practice that this can best be done by means of heat but difficulty has been experienced in subjecting the hair to an ironing action while being heated.

An object of the present invention is to provide 10 a simple, compact and efficient device which can be handled readily and, after being heated, can be drawn through the hair and at the same time hold the hair under compression so as to effect an ironing action sufficient to remove the objectionable kinks.

With the foregoing and other objects in view which will appear as the description proceeds, the invention consists of certain novel details of construction and combinations of parts hereinafter more fully described and pointed out in 20 the claims, it being understood that changes may be made in the construction and arrangement of parts without departing from the spirit of the invention as claimed.

25 In the accompanying drawing the preferred form of the invention has been shown.

In said drawing

Figure 1 is a plan view of the device.

Figure 2 is a section on line 2—2, Figure 1.

30 Figure 3 is a plan view with the cover plate removed, a portion of one end being in section.

Figure 4 is an enlarged section through a portion of the device showing the connection between the sliding plate and its operating lever.

35 Figure 5 is a section on line 5—5, Figure 2.

Referring to the figures by characters of reference 1 designates the body of the device which is in the form of a plate having a recess 2 in the top space thereof. This recess extends from front 40 to back of the plate and is formed with side walls 3 to one of which is secured a spring 4 extending into the recess.

Guard plates 5 are extended forwardly from the sides of the plate and interposed between them are regularly spaced teeth 6 which are integral with the plate. These teeth are preferably tapered in height to blunt points at their forward ends shown particularly in Figure 2.

45 A slidable plate 7 is mounted in the recess 2, its length being somewhat less than the distance between the side walls of the recess. Spring 4 bears against one end of this sliding plate and holds it normally thrust against the opposed wall of the recess. Extending from this slidable plate 50 along one end thereof are regularly spaced teeth

8 similar to the teeth 6 and interposed between them. It will be noted, by referring to Figure 5, that all of the teeth have their edges rounded although their side faces are flat so as to form ironing surfaces.

5 A loop 9 is extended upwardly from plate 1 and through a slot 10 formed within a cover plate 11 which is fastened to the plate 1 in any suitable manner, as by means of corner screws 12. A socket 13 is provided on this cover plate for the 10 reception of one end of a handle 14 and this handle carries a collar 15 from which extends an ear 16. An operating lever 17 is journaled in this ear and has one end extending into engagement with the loop 9 while its other end is 15 supported adjacent to the handle 14 where it can be gripped and actuated readily by the operator. A guide pin 18 can be extended from lever 17 so as to work within an opening 19 in the handle.

In practice this device is thoroughly heated. 20 Thereafter the teeth are inserted into the hair of the person being treated and lever 17 is shifted so as to slide plate 7 against the action of the spring 4 and cause the teeth 8 to move toward the teeth 6. Thus the hair will be gripped firmly 25 between the flat faces of the cooperating teeth and by then pulling these heated teeth through the hair they will act to iron out the artificial or natural kinks and thus quickly prepare the hair for dressing. Both plates 1 and 7 will retain heat for a considerable length of time and this will be transmitted by conduction to the teeth 6 and 8 with the result that frequent reheating will not be required.

30 35 What is claimed is:

1. A hair pressing comb including a plate having a recess in one face and teeth extending from the plate, a slide mounted in the recess, teeth extending therefrom and between the teeth on the plate, a spring at one end of the recess bearing 40 against the slide to hold it normally in a predetermined position with its teeth spaced from the teeth of the plate, a cover plate joined to the recessed plate and overlying the slide, a handle on the cover plate, and means connected to the 45 handle for actuating the slide to move its teeth against the action of the spring toward and from the other teeth.

2. A hair pressing comb including a base plate having a recess, teeth extending from one edge of 50 the plate and disposed at one end of the recess, a slidable plate in the recess, a spring in the recess for holding the slidable plate normally pressed in one direction, teeth on the slidable plate extending between and normally spaced 55

from the teeth on the base plate, a cover plate secured to the base plate and having a slot, a handle extending from the cover plate, an actuating element carried by the handle, and means on the slidable plate extending through the slot for engagement by the actuating element.

3. A hair pressing comb including a base plate having a recess open at the front and back, guard teeth extending from the sides of the plate, parallel teeth interposed between the guard teeth and extending from the base plate, a plate slidable in the recess, yielding means in the recess for holding the plate normally pressed against one end

of the recess, teeth extending from one edge of the slidable plate and between the teeth on the base plate, all of the teeth being normally spaced apart, a cover plate extending over the recess, a handle thereon, an operating element carried by the handle, and means on the slidable plate for engagement by the operating element to shift the slidable plate away from normal position and move its teeth toward the teeth on the base plate, all of the teeth having flat ironing faces with rounded edges.

JAMES DUCKWORTH.
